RADIO APPARATUS

William J. Larkin, Jr., Lynnfield, Mass., assignor
to National Company, Inc., Malden, Mass., a
corporation of Massachusetts

Application September 11, 1939, Serial No. 294,260

2 Claims. (Cl. 175—41.5)

This invention relates to radio apparatus and comprises an improved variable condenser particularly adapted to be mounted on an improved support.

With the tremendous increase in the use of mobile transmitting and receiving apparatus in police cars, yachts, automobiles, and aircraft has come a demand for compactness and rigidity. Designers of radio equipment are required to space the various elements closely together and to mount them rigidly in place in order to avoid short circuits and changes in distributed capacities which might otherwise result from shocks and the motion to which the apparatus is subjected.

It has been the practice to secure radio frequency chokes and small condensers to the chassis of a radio set merely by the lead wires which are soldered to the various connected elements, a practice which results in the disadvantages suggested in the foregoing paragraph. The most important object of my invention is to provide means for detachably but rigidly securing chokes or condensers to the chassis or panel of a radio set, so that shocks due to movement of the set will not change the position of the mounted elements.

An important feature of my invention resides in a stand-off insulator provided with means for attachment to a panel or chassis and to a choke or condenser.

Another feature of my invention consists in a novel variable condenser so constructed as to take up very little room and which may be located closely adjacent a tube or other element so that the leads therefrom are of the minimum length.

A further feature of my invention resides in a support, core, and caps constructed and arranged so that they may be cooperatively assembled in the organization of a choke coil or a condenser as desired.

These and other objects and features of my invention will be more readily understood and appreciated from the following detailed description of preferred embodiments thereof, selected for purposes of illustration and shown in the accompanying drawing, in which:

Fig. 1 is an exploded view in perspective of a condenser and support therefor.

Fig. 2 is a view in cross section of a condenser and its support also suggesting its location adjacent a vacuum tube, and

Fig. 3 is a view in side elevation of a radio frequency choke constructed according to the invention.

The improved support constructed according to my invention and as shown in the drawing comprises a frusto-conical stand-off insulator 10 of porcelain, steatite, or other good insulating material. The insulator 10 as shown in Figs. 1 and 2 is axially recessed and tapped at the top and bottom and is adapted to support a condenser. The body of the condenser is a hollow elongated core 12 of porcelain or other dielectric material which has metal caps 14 and 16 die cast on both ends, a washer 13 of phenolin resin or similar material being pressed in the lower end of the core 12 to prevent metal from entering the interior thereof during the die casting operation. The bottom cap 14 has an integral short screw or stem 18 which threads into the tip of the insulator 10, and the upper cap 16 is internally threaded to receive a long screw 22 having a lock nut 20 and a knurled head. Integral with the bottom cap 14 is an elongated metal sleeve 24 which surrounds the core 12. The metal of the caps and the sleeve is a good conductor of electricity, and lead wires 26 are secured to the caps 14 and 16. The screw 22 makes good contact with the cap 16 and thus with the upper lead wire 26, while the sleeve 24 is electrically connected to the lower lead wire. It will be apparent that the sleeve 24, the core 12, and the screw 22 form respectively the stator, dielectric, and rotor of a small condenser wherein the capacity may be varied by turning the screw 22 to change the amount of its length which lies within the compass of the sleeve 24.

The insulator 10 is secured by a screw 30 to the chassis or panel 28 of a radio set, whether transmitter or receiver, so that the condenser is either vertically or horizontally mounted depending upon whether the member 28 is the chassis or a panel. It will be apparent that the condenser takes up very little space on the panel or chassis and that it is held securely in position to withstand shocks.

The condenser on its support 10 is particularly well adapted for use as a neutralizing condenser in the push-pull circuit of a radio transmitter. In Fig. 2 a vacuum tube 32 is shown (diagrammatically) in its socket 34 adjacent the condenser. The upper lead wire 26 goes directly from the condenser to the grid cap 36 of the tube 32 while the lower lead 26 goes to one of the contact points 38 of the socket 34. In high frequency radio apparatus it is highly important and necessary to keep the leads as short as possible to minimize stray and distributed capacities, and in view of this fact my novel support

offers important advantages in radio construction.

In Fig. 3 my invention is shown embodied in a radio frequency choke. In this example it includes a frusto-conical insulator 40 secured to the panel or chassis 42 by a screw 44. The choke consists of a core 46 of steatite or other suitable insulating material which is secured to the top of the insulator 40 by means of a screw 48 integral with a metal cap 50 which is secured to the lower end of the core 46. A coil 54 is wound in four sections around the core 46 and its ends are soldered to the caps 50 and 52, which also carry lead wires 56. Like the condenser, the choke 15 may be mounted vertically or horizontally near the elements to which it is to be connected. It will be obvious that the coil of the choke is delicate and my novel support has the advantage of holding the choke rigidly so that it cannot 20 come into contact with elements in the set which might disturb the winding or break the wire.

It should be pointed out that many of the elements of the choke are interchangeable with those of the condenser. The stand-off insulator, 25 core, and caps are the same. This fact renders the cost of the elements very low, since the number of special parts is thus materially reduced.

The foregoing description will suffice to indicate the nature of my invention to those skilled 30 in the art, and it should be pointed out that my invention includes within its scope the modifications which may be necessary or desirable when incorporating the choke or condenser into radio sets of various designs. Furthermore the choke 35 shown is only one of many types commonly used and which may be mounted in similar fashion.

Having thus disclosed my invention and described in detail specific embodiments thereof I claim as new and desire to secure by Letters Patent of the United States:

1. A variable condenser comprising an elongated core of insulating material having an axial passage therein, a metal cap surrounding one end of the core and having a screw threaded aperture co-axial with the passage in the core, an insulating disc closing the other end of the 10 passage in the core, a solid cap surrounding the closed end of the core, a cylindrical sleeve integral with the solid cap and surrounding a portion of the core, a threaded mounting stem integral with the solid cap, and an elongated 15 threaded rod disposed in the passage in spaced relation with the wall thereof and movable axially therein.

2. A variable condenser comprising an elongated core of insulating material having an axial 20 passage therethrough, a metal cap surrounding one end of said core and having a screw threaded aperture therein smaller in diameter than the diameter of the axial passage, a solid metal cap 25 surrounding the other end of the core, an insulating disc disposed in the end of said passage adjacent the solid metal cap, a cylindrical sleeve integral with the solid cap and surrounding only a portion of the core, a screw threaded mounting stem also integral with the solid cap, and an 30 elongated screw threaded in the apertured cap and movable axially in the passage in the core.

WILLIAM J. LARKIN, JR.
